(57) CLAIM

The ornamental design for a shoe with blue sole as shown and described.

DESCRIPTION

FIG. 1 is a perspective view of an embodiment of our new design of a shoe with blue sole, in which the sole is hatched using the USPTO convention of horizontal lines for blue (e.g., Pantone 277-Pantone 314, any one of Pantone 317-Pantone 320, Pantone 325 or Pantone 326, any one of Pantone 532-Pantone 552, any one of Pantone 628-Pantone 662, Pantone 801, Pantone 808, any one of Pantone 2702-Pantone 2708, Pantone 2717 or Pantone 2718, Pantone 2727 or Pantone 2728, Pantone 2747 or Pantone 2748, Pantone 2757 or Pantone 2758, Pantone 2767 or Pantone 2768, any one of Pantone 2905-Pantone 3165, any one of Pantone 3242-Pantone 3278, any one of Pantone 5395-Pantone 5435, any one of Pantone 7453-Pantone 7477, any one of Pantone 7541-Pantone 7547, or any one of RAL 5000-RAL 5026); FIG. 2 is a first side view thereof; FIG. 3 is a second side view thereof; FIG. 4 is a top view thereof; FIG. 5 is a bottom view thereof; FIG. 6 is a front view thereof; and, FIG. 7 is a back view thereof.

The broken lines in the figure views depict portions of the shoe that form no part of the claimed design.
